UNITED STATES PATENT OFFICE

2,486,564

STOVE CONSTRUCTION

George W. Kamin, Lombard, Ill., assignor to
 Cribben and Sexton Company, Chicago, Ill., a
 corporation of Illinois

Application October 3, 1945, Serial No. 619,953

4 Claims. (Cl. 126—41)

1

The invention relates to a stove construction, and more particularly to a stove construction having an automatically elevated broiler plate.

An object of the invention is to provide a broiler grill with a spring or counterbalance to compensate for the load placed on the grill.

It is a still further object of the invention to provide a broiler which is automatically elevated and lowered with respect to an adjustable position.

It is a more specific object of the invention to provide an adjustable broiler plate stop.

Further objects and advantages will be apparent from the following description and the drawing appended thereto.

In the drawing, in which like reference characters refer to like parts:

Fig. 1 is a perspective view of a stove construction embodying the invention;

Fig. 2 is an enlarged, elevational view in section of the embodiment illustrated in Fig. 1 in which the broiler drawer is in an open position;

Fig. 3 is a view similar to that of Fig. 2 in which the broiler drawer is in a closed position;

Fig. 4 is a view taken on lines 4—4 of Fig. 2; and

Fig. 5 is a view taken on line 5—5 of Fig. 2.

In the preferred embodiment of the invention as illustrated in the drawings, the stove construction 10 comprises a broiler drawer 11 having bottom 12, sides 13, and front 14. The drawer 11, furnished with a suitable handle 16, is adapted to fit within broiler compartment 15.

Broiler plate 17 is mounted within the drawer by supporting members 18 which are pivotally connected to flanges 19 of the plate and to bottom 12 of the drawer. Where the supporting members 18 are pivotally connected to the sides 13 on its outside edges as shown in the drawings, such members extend inside of the drawer through slits 21 of drawer sides 13. The slits 21 are of sufficient length to accommodate the supporting members as they are pivoted on sides 13. At least two supporting members 18 are utilized to support a removable plate 17 upon the frame 17a, so that the plate may be maintained in a horizontal position. The pan or plate 17 is in effect pivotally supported upon the members 18 through the frame 17a.

Movement of supporting members 18 is provided by arms 22 which engage the members 18 by means of fingers 23. Arm 22 is pivotally connected to the drawer side 13. Stabilizer 24 is also pivotally connected to a side 13 of the drawer. Connecting element 25 is pivotally connected to

2

the upper end of stabilizer 24 and arm 22. Spring 26 is secured to bottom 12 and bears against stabilizer 24 to force the stabilizer away from the drawer.

Means for elevating the broiler pan 17 is secured to connecting element 25 and stabilizer 24 at their pivotal connection. The elevating means may comprise roller 27 which is adapted to engage track 28 on the inside walls of the broiler compartment 15. The movement of roller 27 upwardly causes arm 22 to be pivoted into engagement with support 18. As support 18 is moved with the arm, broiler plate 17 is raised from the bottom of the drawer while being maintained in a horizontal position.

Track 28, secured to the sides of broiler compartment 15 by fastening means 32, causes roller 27 to be moved upwardly or downwardly depending upon whether the broiler drawer 11 is being opened or closed. Track 28 comprises a lower portion 29 extending substantially the depth of the broiler compartment and an inclined portion 31 near the front of the compartment. Inclined portion 31 is of sufficient length to move the roller 27 upwardly to its fullest extent. When the broiler drawer 11 is closed as shown in Fig. 3, roller 27 occupies lower position 29 in the track, such position causing arm 22 to be pivoted forward so that broiler plate 17 is not in its elevated position.

Upon opening the broiler drawer, roller 27 is forced into inclined portion 31 and is then moved upwardly to its full extent, thereby elevating broiler plate 17. Upon closing the broiler drawer 11, roller 27 is moved downwardly by inclined portion 31 and into lower position 29, thereby pivoting arm 22 in a forward direction and releasing plate 17 from its elevated position.

The action of track 28 upon roller 27 is dependent to some extent upon the strength of spring 26. Where a spring 26 is used that only partially compensates for the weight of plate 17, the lower edge of portion 31 bears against roller 27 and forces the roller upwardly as the drawer is opened. Upon closing the drawer, roller 27 is permitted to move downwardly in portion 31, thereby releasing plate 17.

Where a spring 26 is used that more than compensates for the weight of plate 17 and the load borne by the plate, the spring forces roller 27 into contact with the upper edge of the track in both the lower portion 29 and inclined portion 31. In this construction, the roller is released upwardly upon entering inclined portion 31, such upward movement being controlled by the upper

edge of the inclined portion. Upon closing the drawer, the roller bears against the upper edge of the inclined portion and is forced downwardly into lower portion 29.

In the preferred embodiment of the invention, a spring 26 is used that is of sufficient strength to compensate for the weight of plate 17 and its supporting members together with the weight of the average load carried by the broiler plate. A spring of this strength permits the drawer to be easily opened and closed by causing track 28 to merely guide the roller as the drawer is being operated.

The broiler pan 17 may be positioned at a desired distance from burner 33 in the broiler compartment by means of adjustable stop 34. Stop 34 comprises member 35 freely supported on the same pivot which supports the adjacent member 18. The free end of member 35 includes pin 37 which is insertable into openings 38 disposed vertically in sides 13. Downward movement of the pan 17 is halted by the engagement of the forward member 18 with the finger 36 on arm 35.

In adjusting the position of pan or plate 17, member 35 is pivoted until the pin 37 is in alignment with a selected opening that will cause the plate 17 to be supported at the desired distance from burner 33. The pin is then inserted in the opening and the drawer 11 is closed. Pan 17 is released by the movement of roller 27 and moves downward until stopped by pin 37. The continued forward movement of the arm 22 is provided by the free engagement of finger 23 with supporting member 18.

Conventional telescoping slides 39 may be provided on either side of broiler compartment 15 to facilitate movement of the drawer within the compartment. The slides 39 engage flanges 41 extending from the bottom edge element 41a on the sides of the drawer.

The above detailed description is given for purposes of illustration and the invention is to be limited only by the scope of the appended claims.

I claim:

1. In a range providing a broiler compartment and a track along at least one side of said compartment and having an upwardly curved end portion, a drawer slidably mounted in said compartment, arms pivotally mounted in the lower portion of said drawer, a plate carried by the upper ends of said arms, a roller mounted in said track, a spring urging said roller in an upward direction, and link means connected to said roller and engaging at least one of said arms to raise said arm and the plate carried thereby when said drawer is drawn outwardly from said compartment to bring said roller into said upwardly curved track portion.

2. In a range providing a broiler compartment and a track along at least one side of said com-

partment and having an upwardly curved end portion, a drawer slidably mounted in said compartment, arms pivotally mounted in the lower portion of said drawer, a plate carried by the upper ends of said arms, a roller mounted in said track, spring means urging said roller upwardly, and link means connected to said roller and engaging at least one of said arms to raise said arm and the plate carried thereby when said drawer is drawn outwardly from said compartment to bring said roller into said upwardly curved track portion, said link means releasing said arm to permit said plate to swing to lowered position when said drawer is moved into said compartment.

3. In a range equipped with a drawer compartment and a broiler burner, a broiler drawer slidably mounted in said compartment and equipped with a broiler plate, parallel arms mounted in said drawer for moving said broiler plate upwardly and downwardly in an arc, a link member engaging one of said arms when said link is moved in one direction only, a cam track mounted within in said range compartment and provided with a roller, link means connecting said roller to said first-mentioned link member, said track having an upwardly-turned outer end portion, and a spring normally urging said roller upwardly.

4. In a range equipped with a drawer compartment and a broiler burner, a broiler drawer slidably mounted in said compartment and equipped with a broiler plate, parallel arms mounted in said drawer for moving said broiler plate upwardly and downwardly in an arc, a link member engaging one of said arms when said link is moved in one direction only, a cam track mounted within in said range compartment and provided with a roller, said track having an upwardly turned end portion, link means connecting said roller to said first-mentioned link member, a spring compressed by the closing of the drawer normally urging said roller upwardly in said upwardly turned track portion and adjustable stop means for limiting the downward movement of said broiler plate.
